UNITED STATES PATENT OFFICE.

WILLIAM R. LYNCH, OF ORTIZ, COLORADO.

CARTRIDGE-BELT.

1,085,451.

Specification of Letters Patent. Patented Jan. 27, 1914.

Application filed September 13, 1912. Serial No. 720,264.

To all whom it may concern:

Be it known that I, WILLIAM R. LYNCH, a citizen of the United States, residing at Ortiz, in the county of Conejos and State of Colorado, have invented new and useful Improvements in Cartridge-Belts, of which the following is a specification.

An object of the invention is to provide a belt for supporting cartridges or shot gun shells around the waist of the wearer.

The invention embodies, among other features, a belt member adapted to encircle the waist of the wearer and having suitable means for securing the ends thereof, a supporting member on the said belt member for supporting an adjustable strap in the plane of the belt member, and a series of spaced strips on the supporting member for forming bulging portions on the said adjustable strap and between the said strips, cartridges or shells being arranged to extend through the bulging portions of the said adjustable strap so that the cartridges or shells will be supported around the waist of the wearer, the strap being adjustable for the purpose of accommodating cartridges or shells of various sizes and shapes.

In the further disclosure of the invention reference is to be had to the accompanying drawings, constituting a part of this specification, in which similar characters of reference denote corresponding parts in all the views, and in which:

Figure 1 is a side elevation of the belt showing a series of cartridges or shells mounted thereon; Fig. 2 is a vertical transverse sectional view taken on the line 2-2 in Fig. 1; and Fig. 3 is a fragmentary horizontal longitudinal sectional view taken on the line 3-3 in Fig. 1.

Referring more particularly to the views, use is made of a belt member 10, adapted to encircle the waist and provided at one end with a plurality of buckles 11 adapted to receive therethrough straps 12 secured to the other end of the belt member 10, for the purpose of supporting the belt member around the waist of the wearer.

A supporting member 13 is sewed or otherwise secured to the belt member 10 on the outer face thereof and is arranged in the longitudinal plane of the belt member, a series of strips 14 being formed with the supporting member 13 and spaced apart as shown, with the said strips extending transversely through the supporting member and

across a guideway 15, for an adjustable strap 16, the said guideway 15 being formed by the longitudinal inner edges of the supporting member 13.

The adjustable strap 16 has one end thereof sewed or otherwise secured to the belt member 10, adjacent the buckles 11 and the strap 16 is then passed through the guideway 15, beneath the strips 14, the edges of the supporting member 13 being adapted to support a strap on the belt member 10 with the free end of the strap adapted for engagement with a buckle 17 secured to the belt member 10 adjacent the straps 12. In order to retain the free end of the strap 16 in position on the belt member 10 and also guide the strap toward the buckle 17, a reinforcing loop 20 is sewed or secured to the belt member 10 adjacent one end of the supporting member 13, as shown in Fig. 1. It will now be seen that when the strap 16 is loosened on the buckle 17, a cartridge 18 can be readily supported on the belt by passing the cartridge beneath the strap 16 and between two of the strips 14, thus causing the strap to project beyond the strips 14 and form a bulging portion or pocket 19, through which pocket the cartridge 18 extends and by which the cartridge is supported.

It will be readily seen that by tightening or loosening the strap 16 relatively to the buckle 17 cartridges or shells of various sizes and shapes can be readily accommodated in the pockets of the strap and it will be further seen that by having the belt member 10 made of a solid piece of leather or the like with the supporting member 13 secured to the belt member so that the bulging portions 19 will project outwardly from the belt member, the belt when applied to the wearer will not inconvenience the same or cause any discomfort to the wearer inasmuch as the flat or inner side of the belt member will be smooth and unruffled and will not dig into the flesh of the wearer regardless of the number of cartridges that are supported on the belt, or the size and shape of the cartridges.

If desirable, the strap 16 can be made of an elastic or flexible material with both ends of the strap rigidly secured to the belt member 10 and it will be readily understood that although I preferably construct my device of leather, the same can be readily constructed of canvas or any other adaptable material.

Having thus described my invention, I claim:

As a new article of manufacture, a belt comprising a belt member for attachment to the body of the wearer, a supporting member on the belt member and extending along the outer face thereof, the said supporting member forming a guideway on the belt member, the said supporting member having a series of parallel transverse slits cut therein to form a series of transversely extending strips, a strap having rigid connection with one end of the belt member and extending through the said guideway and

beneath the said strips, with the intermediate portions of the strap between the strips bulged to receive cartridges, and a buckle carried on the belt member and adapted to receive the free end of the strap for reducing the bulged portions between the said strips to bind the said cartridges to the said supporting member. 15

In testimony whereof I affix my signature in presence of two witnesses.

WILLIAM R. LYNCH.

Witnesses:
